US00D530810S

(12) **United States Design Patent** (10) **Patent No.:** **US D530,810 S**
Hidalgo et al. (45) **Date of Patent:** **** Oct. 24, 2006**

(54) **COMBINED CEILING FAN HOUSING AND ROTATABLE ARMS UNIT**

(75) Inventors: **Rolando Hidalgo**, Orange, CA (US); **Mark Gajewski**, Avila Beach, CA (US)

(73) Assignee: **Minka Lighting, Inc.**, Corona, CA (US)

(**) Term: **14 Years**

(21) Appl. No.: **29/234,474**

(22) Filed: **Jul. 19, 2005**

(51) **LOC (8) Cl.** **23-04**

(52) **U.S. Cl.** **D23/411**

(58) **Field of Classification Search** D23/377, D23/379, 385, 411, 413; 392/364; 416/5

See application file for complete search history.

(57) **CLAIM**

The ornamental design for a combined ceiling fan housing and rotatable arms unit, as shown and described.

DESCRIPTION

FIG. 1 is a perspective view from below of a combined ceiling fan housing and rotatable arms unit in accordance with our design;

FIG. 2 is a top plan view of the combined ceiling fan housing and rotatable arms unit in accordance with our design;

FIG. 3 is a bottom plan view of the combined ceiling fan housing and rotatable arms unit in accordance with our design;

FIG. 4 is a side elevation view of the combined ceiling fan housing and rotatable arms unit in accordance with our design, the opposite side being a mirror image of that shown; and,

FIG. 5 is a front perspective view from below of the combined ceiling fan housing and rotatable arms unit in accordance with our design.

The broken lines showing environmental structure are for illustrative purposes and form no part of the claimed invention.
